UNITED STATES PATENT OFFICE.

WASHINGTON M. DILLON AND PETER FRANTZ, OF STERLING, ILLINOIS.

CRIMPING MECHANISM FOR WIRE-FENCE MACHINES.

No. 813,408.

Specification of Letters Patent.

Patented Feb. 27, 1906.

Application filed August 17, 1904. Renewed August 17, 1905. Serial No. 274,645.

To all whom it may concern:

Be it known that we, WASHINGTON M. DILLON and PETER FRANTZ, citizens of the United States, residing at Sterling, in the county of Whiteside and State of Illinois, have invented 5 certain new and useful Improvements in Crimping Mechanism for Wire-Fence Machines; and we do declare the following to be a full, clear, and exact description of the invention, such as will enable others skilled in the art to which it appertains to make and use the same, reference being had to the accompanying drawings, and to the characters of reference marked thereon, which form a 15 part of this specification.

Our invention has reference to crimping mechanism for wire-fence machines, and is specially designed to assist in producing the style of fence shown and described in Letters 20 Patent of the United States No. 755,637, issued March 29, 1904, to W. M. Dillon.

In the present application our invention is shown as substituted for the crimping devices illustrated and set forth in Letters Patent of 25 the United States No. 739,846, issued September 29, 1903, to P. Frantz; but by changes in the structure and arrangement of the parts the same can be adapted to be used in other machines which produce a square-mesh fence. 30 In the following specification only those parts of the old machine will be referred to which are pertinent to the operation of the crimping mechanism.

In the drawings, Figure 1 is a plan view of 35 a machine embodying our invention with some of the parts removed. Fig. 2 is a side elevation of the rear portion of the machine, showing parts of our invention in end view. Fig. 3 is a vertical section in the line 3 3 of 40 Fig. 1. Fig. 4 shows parts of the operating mechanism of our invention in detail. Fig. 5 is an enlarged detail of parts thereof in plan view. Fig. 6 is a detail of one of the dies 18 in elevation. Fig. 7 is a plan view of our device in detail.

Similar characters refer to similar parts throughout the several views.

1 1 represent the frame of the machine, united at each end by cross-plates 2 and 3. 50 Journaled on the under side of the frame 1 is a main shaft 4, at one end of which the power is applied in any usual method to operate the machine. On the opposite end of the shaft 4 is a gear-pinion 5, actuating a gear-wheel 6 on 55 the end of a rotary shaft 7, supported beneath the frame 1, parallel with the shaft 4.

8 8 represent a series of strand-wires in their progress through the machine, and 9 9 transverse wires, having their ends coiled upon the strand-wires at regular intervals to 60 form the fence. The wires 8 are suitably drawn through the machine with an intermittent or step-by-step movement.

Pivotedly secured to the cross-plate 2, as at a, Fig. 3, is a pair of levers 10, provided at 65 their free ends with rollers 11, which engage the faces of a pair of cam-wheels 12, fixed on the shaft 7, such levers being supported at their free ends by the cams 12. Having virtual movement in ways 13 on the inner faces 70 of the frame is a cross-bar 14, such bar being supported on the levers 10 by means of slide-blocks 15 on the lower face of such bar. A channel 16 extends longitudinally of the bar 14, supported in such channel being a slide-bar 75 17, so as to be capable of reciprocating movement therein transversely of the machine. Fixed on the bar 14 is a series of dies 18, and on the bar 17 is secured a series of dies 19, corresponding in number with the dies 18 80 and adapted to be brought simultaneously into proximity with said last-named dies upon the bar 17 being suitably operated. Fulcrumed in the channel 16 beneath the bar 17 is a bell-crank lever 20, having its upper 85 arm secured to the slide-bar 17 by means of a link 21. Fixed on the shaft 7 is a cam 22, having a track 23, engaged by a follower 24, projecting from the lower arm of the lever 20. By this means each rotation of the shaft 7 operates to reciprocate the bar 17 and bring the 90 dies 19 into proximity with the dies 18.

Transversely of the die 18 is a V-shaped channel 25, and the die 19 is similarly provided with a channel 26. The dies 18 and 95 19 are so disposed upon the bars 14 and 17, respectively, that the space between each pair thereof is just below one of the strand-wires 8, and in the crimping operation said wires are embraced between the several pairs of 100 dies, the wires 9 being accommodated by the channels 25 and 26. When in this position, the coils of each adjacent pair of stay-wires are held from lateral movement by ribs 27 and 28 on the inner faces of the dies 18 and 105 19, respectively, the strand-wire being bent or crimped on one side of the coils by a jaw 29 on the die 18 and on the other side of the coils by a similar jaw 30 on the die 19. The strand-wire is further held while being crimped 110 by vertical ribs 31 and 32 on the dies 18 and 19, respectively.

Secured at each side on the frame 1 is a pair of supports 33, in the upper ends of which is journaled a rock-shaft 34, fixed on which is a pair of levers 35, having the ends of their long arms loosely connected with the levers 10 by means of the vertical rods 36. Depending from the short ends of the levers 35 is a pair of racks 37, supporting at their lower ends a pair of transverse parallel bars 38, which are normally held a short distance above the wires 8, so as not to interfere with the passage thereof. Journaled in the supports 33 is a rock-shaft 39, fixed on which is a series of short arms 40, having at their outer ends claws 41. The arrangement of the arms 40 is such that each of the strand-wires 8 is adapted to be embraced by one of the claws 41 upon the proper operation of thereof. To the end of the shaft 39 is secured an arm 42, provided with a roller 43, engaging the face of a cam-wheel 44 on one end of the shaft 7.

To recapitulate, the operation of the crimping mechanism is as follows: In the progress of the wires 8 through the machine and after the wires 9 have been secured thereon each intermittent movement of the strand-wires operates to bring a series of stay-wires immediately above the crimping-bar in position to be engaged by the dies thereon. By the rotation of the cams 12 at the proper time the levers 10 and bar 14 are raised until each of the wires 8 occupies one of the spaces between one pair of dies 18 and 19. The upward movement of the levers 10 rocks the levers 35, resulting in the downward movement of the racks 37 and bars 38 until such bars rest upon the wires 8 on each side of the bar 14 and prevent the accidental movement of the wires from between the dies. While in this position the bar 17 is reciprocated, bringing the dies 19 into close proximity with the dies 18 and forming the crimps in the strand-wires. In the forming of the crimp there is a tendency to force that part of the strand-wire adjacent thereto out of line, which tendency is overcome by the use of the ribs 31 and 32 on the inner faces of the dies. The rock-shaft 39 and claws 41 constitute an auxiliary device which may be used or not, as desired, the purpose thereof being to overcome any danger of the stay-wires getting out of alignment, so as not to properly enter the channels 25 and 26 in the dies. When such parts are used, as the wires 8 near the end of a movement, the shaft 39 rocks sufficiently to cause the claws 41 to engage the wires 8 and hold any stay-wires which may be in advance of the other stay-wires until such other wires come in line therewith. As the bar 14 is raised the claws are again elevated, so as not to interfere with the dies thereon. After the crimps have been formed in the wires the dies again separate through the return movement of the bar 17, and the bar 14 is lowered to permit the further passage of the wires.

What we claim as our invention, and desire to secure by Letters Patent of the United States, is—

1. A crimping device for wire-fence machines, comprising a crimping-bar, capable of vertical play in the machine; a series of stationary dies, fixed on said bar; a slide-bar, adapted to be supported in said crimping-bar, so as to oscillate therein; a series of dies, secured on said slide-bar, and adapted to be severally brought into proximity with one of said stationary dies upon the proper operation of said slide-bar, the adjacent faces of the several pairs of dies being adapted to suitably embrace the strand-wires of the fence and crimp the same on opposite sides of the stay-wire coils; a pair of parallel cross-bars, on opposite sides of the crimping-bar; means for suitably raising and lowering the crimping-bar; means for suitably oscillating said slide-bar, to bring said last-named dies into proximity with said first-named series of dies; and means for lowering said parallel bars upon the strand-wires simultaneously with the raising of said crimping-bar, substantially as shown and set forth.

2. In a crimping device for wire-fence machines, the combination, with the frame 1, of the cross-bar 14, having vertical play therein, and provided with the channel 16, the slide-bar 17, supported in the bar 14, and adapted to oscillate therein; the dies 18, fixed on the bar 14, and provided on their inner faces with ribs 27 and jaws 29; the dies 19, fixed on the slide-bar 17, and provided on their inner faces with ribs 28 and jaws 30; means for suitably raising and lowering the bar 14, and means for suitably oscillating the slide-bar 17, to bring the adjacent faces of the dies 18 and 19 into proximity, substantially as shown and described.

3. In a crimping device for wire-fence machines, the combination of the vertically-movable bar 14, suitably mounted in the machine; and provided on its upper face with a series of dies 18, the slide-bar 17, supported in the bar 14 so as to have oscillation therein, and provided on its upper face with the dies 19, the rock-shaft 39 suitably mounted on the frame 1, the series of arms 40, secured on the shaft 39 and provided with claws 41; means for suitably rocking the shaft 39; means for raising and lowering the bar 14, and means for oscillating the slide-bar 17, substantially as set forth.

4. In a crimping device for wire-fence machines, the combination of the bar 14, provided with the channel 16; the slide-bar 17, suitably mounted in the recess 16, to oscillate therein; the series of dies 18, fixed on the upper face of the bar 14; the series of dies 19, fixed on the upper face of the slide-bar 17, and adapted to be brought into proximity with the dies 18, upon the oscillation of the bar 17, the parallel bars 38, suitably sup-

ported on opposite sides of the bar 14; the arms 40, suitably mounted above the strand-wires of the fence and provided with claws 41; means for operating the arms 40, to cause the claws thereon to engage said strand-wires; 5 means for raising the bar 14; means for simultaneously lowering the bars 38; and means for oscillating the slide-bar 17, substantially as shown and set forth.

10 5. In a crimping device for wire-fence machines, the combination of the oscillating bar 17, provided with a series of dies 19, the lever 20, pivoted beneath said bar 17, and connected therewith by means of the link 21, and 15 means for operating the lever 20 to oscillate the bar 17, substantially as set forth.

6. In a crimping device for wire-fence machines, the combination of the rock-shaft 34, suitably mounted on the frame of the 20 machine; the arms 35, fixed thereon, racks 37, supported by the arms 35; cross-bars 38, supported by the racks 37; and means for suitably operating the arms 35; substantially as shown and described.

25 7. In a crimping device for wire-fence ma-

chines, wherein the fence is formed with series of stay-wires in substantial alinement transversely of the fence, the combination, with series of dies adapted to form crimps in the strand-wires of the fence at the points of junction of the stay-wires therewith, of a rock-shaft, a series of arms mounted on such rock-shaft, corresponding in number and vertically in line with the strand-wires, such arms being provided with claws adapted to 30 engage the strand-wires, and bring the several stay-wires of a series into transverse alinement thereon, and means for suitably rocking such shaft, substantially as shown.

35 In testimony whereof we affix our signatures in presence of witnesses.
